(57) **CLAIM**

The ornamental design for a beverage dispenser cap, as shown and described.

DESCRIPTION

FIG. 1 is a top, front, and left-side isometric view of a beverage dispenser cap showing our new design;

FIG. 2 is a front elevation view thereof;

FIG. 3 is a rear elevation view thereof;

FIG. 4 is a left-side elevation view thereof;

FIG. 5 is a right-side elevation view thereof; and,

FIG. 6 is a top plan view thereof.

The broken lines in the drawing views are included for the purpose of illustrating unclaimed environment only, and form no part of the claimed design.

1 Claim, 6 Drawing Sheets
